United States Patent Office.

CHARLES B. BRISTOL, OF NEW HAVEN, CONNECTICUT.

Letters Patent No. 67,020, dated July 23, 1867.

IMPROVED SNAP-HOOK.

The Schedule referred to in these Letters Patent and making part of the same.

TO ALL WHOM IT MAY CONCERN:

Be it known that I, CHARLES B. BRISTOL, of the city and county of New Haven, in the State of Connecticut, have invented a new and useful Improvement in Snap-Hooks for Harness, &c.; and I do hereby declare that the following is a full, clear, and exact description of the construction, character, and operation of the same, reference being had to the accompanying drawings, which make part of this specification, in which—

Figure 1 is a perspective view of the snap-hook complete, as seen from the under or back side, showing the bridge across the open space, and the spiral or helical spring in its place.

Figure 2 is a section of the same, cut longitudinally through the centre, showing the bridge, with its projection or stud, the projection or stud on the tongue part, and the spiral spring as resting on or around those two studs.

Figure 3 is a perspective view of the hook and loop parts, (with one of the ears or lips broken away,) showing the bridge with its projecting stud, and one hole for the fulcrum-pin.

Figure 4 is a perspective view of the tongue part, showing the projecting stud and the hole for the fulcrum-pin.

Figure 5 is a perspective view of the spiral or helical spring.

My improvement consists in making in the portion at the junction of the hook and loop an open space between the ears or lips, to prevent its collecting and retaining dirt or ice, and a bridge across it to support a projecting stud, on or around which the lower end of the spiral or helical spring rests and is held in place; and in casting or fitting a projecting stud on the tongue part near the rear end, but forward of the hole, for the fulcrum-pin, which stud is to pass into the upper end of the spiral spring, so as to steady and sustain it; and in the use of the spiral spring, with its two ends passed on to the two projecting studs, to sustain it in its place.

I make the hook and loop part of malleable cast iron, or any other suitable material, in the usual shape, as shown in fig. 3, except that I cast or leave an open space clear through at the junction of the hook A and loop B, between the two ears or lips, as represented at a, figs. 1, 2, and 3; across which space, a, I cast or make a bridge, b, figs. 1, 2, and 3, on which bridge I cast or fit a projecting stud, as represented at e, figs. 2 and 3, on to which the lower end of the spiral spring, d, figs. 1, 2, and 5, passes, as represented in section in fig. 2.

I make the tongue part C, figs. 1, 2, and 4, of malleable cast iron, or any other suitable material, substantially in the form or shape shown in fig. 4, with a projecting stud near the rear end, but forward of the hole g, for the fulcrum-pin, as represented at e, figs. 2 and 4, on to and around which the upper end of the spiral spring passes, and by which it is held in place, as indicated in section at e, fig. 2.

I make the spiral or helical spring of brass or any other suitably elastic wire, in the usual way, as represented in fig. 5, and indicated at d, figs. 1 and 2.

Having made the several parts, as before described, I pass one end of the spiral spring, fig. 5, on to the projecting stud e on the bridge b, as represented in section in fig. 2, and pass the projecting stud e on the tongue part into the upper end of the spiral spring d, as indicated in section in fig. 2, and insert the rivet or fulcrum-pin through the holes in the ears or lips, and the rear end of the tongue part, as at g, figs. 2, 3, and 4, and rivet the fulcrum-pin in the usual way, or otherwise, when the whole will be as represented in fig. 1, and all the parts will be arranged in relation to each other as indicated in section in fig. 2.

The principal advantages in my improvement consist in that by making or leaving an open space entirely through at the junction of the parts, as represented at a, figs. 1, 2, and 3, the snap-hook will never get filled up or clogged with dirt, ice, or other foreign substances, as often happens when the rear end of the tongue part and the spring are fitted into a comparatively close box, as is the case in the Henshaw and the Jadd & Blakesley patents, and many others; and in that, by securing or sustaining the two ends of the spiral spring on or around projecting studs, (as indicated in section in fig. 2;) so that when the tongue is pressed down, (to open the snap-hook,) those studs will nearly touch each other, and they will form a steady support to the spring and cause it to work in a right line (expanding and contracting longitudinally) so as to avoid all lateral or irregular strain on the spring.

What I claim as my invention, and desire to secure by Letters Patent, is—

The combination of the hook and loop part (having a bridge, b, and stud, e,) with the tongue part, (having a stud, e,) and the spiral spring d, when the parts are constructed, arranged, and fitted to operate, substantially as herein described and set forth.

CHAS. B. BRISTOL.
